(57) **CLAIM**

The ornamental design for a universal arm bracket, as shown and described.

DESCRIPTION

FIG. 1 is a rear, right and top perspective view of a universal arm bracket showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a rear, right and top perspective view of the rod in an extended state;

FIG. 10 is a rear, left and top perspective view of the rod in an extended state;

FIG. 11 is the left perspective view of the use state;

FIG. 12 is the left perspective view of the use state in another position;

FIG. 13 is an enlarged partial view of FIG. 1;

FIG. 14 is an enlarged partial view of FIG. 5;

FIG. 15 is an enlarged partial view of FIG. 6; and,

FIG. 16 is an enlarged partial view of FIG. 9.

The broken lines in FIGS. 11 and 12 are for the purpose of illustrating environmental subject matter that forms no part of the claimed design. The remaining broken lines in the drawings are for the purpose of illustrating portions of the universal arm bracket that form no part of the claimed design.
